HANDLE FOR LAWNMOWERS, SNOW BLOWERS OR SIMILAR ARTICLES

Donald L. Gobin, Newark, Ohio, and Robert M. Goodman, Morton Grove, Ill., assignors to Roper Corp., Kankakee, Ill., a corporation of Delaware

Filed July 5, 1968, Ser. No. 12,644

Term of patent 14 years

Int. Cl. D8—01

U.S. Cl. D40—1

FIG. 1 is an elevational view of a handle for lawnmowers, snow blowers or similar articles showing our new design;

FIG. 2 is a top plan view thereof;

FIG. 3 is a bottom plan view thereof;

FIG. 4 is an end elevational view looking in the direction of the arrows 4—4 of FIG. 1;

FIG. 5 is a cross section view taken on line 5—5 of FIG. 1;

FIG. 6 is a cross sectional view taken on line 6—6 of FIG. 1;

FIG. 7 is a cross sectional view taken on line 7—7 of FIG. 1, and

FIG. 8 is a cross sectional view taken on line 8—8 of FIG. 1.

The downwardly extending tubular portions of the handle are shown broken away to indicate indeterminate length.

We claim:

The ornamental design for a handle for lawnmowers, snow blowers or similar articles, as shown and described.
